CURRENT COLLECTOR

Maurice F. Jones, Wilkinsburg, Pa., assignor to
 Westinghouse Electric Corporation, East Pittsburgh, Pa., a corporation of Pennsylvania

Application October 14, 1943, Serial No. 506,199

8 Claims. (Cl. 191—49)

1

My invention relates generally to current collectors, and has reference in particular to current collectors for collecting current from conductor rails and the like.

Generally stated, it is an object of my invention to provide an improved current collector that is simple and inexpensive to manufacture and has improved operating characteristics.

More specifically, it is an object of my invention to provide a current collector wherein a current-collecting shoe is operatively connected to a support which drags the shoe along the conductor rail in either direction of operation of the collector.

An important object of my invention is to provide a current collector of high current carrying capacity which occupies but little space and has a minimum weight.

It is also an object of my invention to provide for increasing the current-collecting capacity of a current collector by improving the operating characteristics and preventing "nosing" or chattering of the shoe in operation.

Another object of my invention is to provide for floatingly mounting a current collector shoe by operatively connecting it to a support so that the shoe may move relative to the support in a plurality of directions in order that it may readily follow deviations in alignment of the conductor from which it collects current.

Yet another object of my invention is to provide for relatively loosely mounting a current collector shoe on a support and biasing it against a conductor so that it may follow deviations in the conductor, and yet provide for but limited movement of the shoe relative to the support, so that it will not move beyond a predetermined position when the collector shoe travels beyond the end of the conductor, and will accordingly be in a position for remaking operating engagement with the conductor when the shoe remakes contact therewith.

Still another object of my invention is to provide for operatively connecting a current collector shoe to a support at points beyond the ends of the shoe so as to permit movement of the shoe in a plurality of directions relative to the support and provide for pulling the shoe in either direction of operation.

A further object of my invention is to provide for resiliently mounting a current collector shoe on a movable support so as to provide for a floating movement of the shoe in a plurality of directions relative to the support.

A still further object of my invention is to pro-

2

vide for operatively connecting a current collector shoe, which is disposed to move along a conductor in opposite directions, to a support member by means of pins adjacent the ends of one member loosely positioned in openings in the other member so spaced that engagement is made between the pin and the edge of the opening at the leading ends of the shoe and the support members in either direction of operation.

10 Other objects will in part be obvious and will in part be explained hereinafter.

In accordance with my invention, a pair of current collector shoes are mounted on elongated drag plates and are positioned on opposite sides 15 of a support plate which operates the shoes. The drag plates are connected adjacent each end by telescoping rivets which fit loosely in openings so spaced in the support plate that the rivet at whichever is the leading end of the shoe engages 20 the support plate and drags the shoe along, and the rivets prevent more than a predetermined displacement of the shoes relative to the support. Springs between the shoes bias them outwardly 25 against current conducting rails between which the shoes ride, and flexible shunts connect the shoes to the support plate so as to provide a current path of high current carrying capacity.

For a more complete understanding of the nature and scope of my invention, reference may be 30 made to the following detailed description which may be read in connection with the accompanying drawings, in which:

Figure 1 is a side elevational view of a current collector embodying the principal features of the invention;

35 Fig. 2 is a sectional view taken along the line II—II of Fig. 1; and

Fig. 3 is a sectional view taken along the line III—III of Fig. 1.

40 Referring to Figs. 1 through 3, a current-collecting assembly is shown, wherein a plurality of current collectors 10 may be secured to a bus 11 mounted on the frame 12 of a vehicle for collecting current from a pair of conductors such as the 45 rails 13.

Each current collector 10 may, as shown, comprise a substantially U-shaped plow or support 44 adapted to be secured to the bus 11 by means such as the bolts 15. The bus 11 may be secured 50 to the frame 12 of the vehicle in any suitable manner, being, for example, mounted thereon by means of insulators 16. The plow may comprise a pair of U-shaped support plates 17 positioned side by side and having dependent legs 18 and 19 at the ends with outwardly deformed end por-

tions 20 adjacent the ends positioned in spaced relation to each other. Openings 21 and 22 may be provided in the end portions of the legs 18 and 19, respectively, for reasons which will be explained hereinafter.

In order to provide for collecting current from the conductor rails 13, a pair of collector shoes 24 of copper graphite or other suitable conducting material may be positioned intermediate the dependent legs 18 and 19 of the plow or support 14. The shoes 24 may be operatively connected to the plow 14 by means of the elongated resilient drag plates 25 of Phosphor bronze strip or the like, which may be secured to the shoes 24 by means of the screws 26.

The drag plates 25 extend beyond the ends of the shoes, and may be operatively connected to each other adjacent the ends so as to provide for relative movement toward or away from each other. For example, the drag plates may be connected by means of rivets 28 comprising telescoping members 29 and 30 secured to the drag plates adjacent the ends thereof.

Means such as the flexible shunts 31 may be provided for electrically connecting the shoes to the plow or support. For example, the shunts 21 may be connected adjacent the ends to the plow or support by being secured between the outwardly deformed end portions thereof and may be secured to the shoes intermediate the ends by means of clamp plates 32 having central openings 33 therein and secured to the shoes by the screws 26.

In order to provide smooth operation of the shoes 24 along the conductor rails 13 and prevent "nosing" or chattering of the shoes, they are preferably connected to the support 14 at points beyond the ends of the shoes. For example, the rivets 28 may be relatively loosely positioned in the openings 21 and 22 in the dependent legs 18 and 19 of the support plates. By so spacing the openings 21 and 22 and the rivets 28 that the distance between the centers of the rivets is slightly less than the distance between the centers of the openings, the shoes 24 may be so operatively connected to the support 14 that they will be actuated by engagement of the rivet 28 with the inner edge of the opening 21 or 22, whichever is at the leading end of the collector regardless of the direction in which the collector is moved. The shoes are thereby pulled or dragged in either direction of operation.

In order to bias the shoes against the rails, means such as the spring 34 may be positioned between the shoes to force them apart. The spring 34 may be positioned in the openings 33 in the clamp plates 32, which are provided for securing the flexible shunt members 31 to the shoes. Since the shoes are biased apart by the springs 34, and are restrained in their movement away from each other by the rivets 28 as well as the shunts 31, they will normally occupy free positions in which they are limited to predetermined distances apart and from the plow or support in any direction. Thus if the collector 10 travels beyond the end of the conductor rail 13, the shoes 24 will not move far from their normal operating position, and operating engagement thereof with the rail may be easily made with a minimum of movement when the shoe returns to the rail.

With the construction hereinbefore described, the shoes 24 are resiliently biased against the conductor rails and are floatingly mounted on the supports for readily following deviations in the rails. In either direction of operation the shoes

are pulled or dragged along the rails and are free to move in a plurality of directions relative to the supports.

From the above description and the accompanying drawings, it will be apparent that I have provided in a simple and effective manner for securing smooth operation of current collector shoes along conductors. By dragging the shoes along the conductor instead of pushing them, "nosing" and chattering of the shoes are prevented. A remarkable increase in the current-collecting capacity of the shoes results, without any apparent increase in the wear of the shoes or without any apparent reduction in the operating life thereof. By resiliently mounting the shoes in floating relation to the support in the manner hereinbefore described, movement of the shoes relative to the support in order to follow deviations in the conductor is readily effected without detriment to the current-collecting characteristics of the shoes, and even though the collectors may travel beyond the ends of the conductors, the shoes are maintained in such positions that they may be readily run back thereon with a minimum of disturbance.

Since certain changes may be made in the above description and different embodiments of the invention may be made without departing from the spirit and scope thereof, it is intended that all the matter contained in the above description and shown in the accompanying drawings shall be considered as illustrative and not in a limiting sense.

I claim as my invention:

1. A current collector comprising, a pair of spaced current collector shoes for engaging the adjacent surfaces of a pair of spaced conductors, means biasing the shoes apart, a pair of drag plates secured one to each shoe, means operatively connecting the drag plates adjacent the ends, and a support having portions thereof positioned between the drag plates with openings for loosely receiving the connecting means.

2. In a current collector for engaging a pair of spaced conductors, a pair of spaced shoes, means positioned between the shoes to bias them apart, a resilient drag plate member secured to each of the shoes, a support member, and means operatively connecting the drag plate members for limited movement relative to each other and to the support member for limited movement relative thereto in a plurality of directions, said means providing a connection with the support member at the leading ends of the drag plates for dragging the shoes.

3. A current collector comprising, a pair of spaced apart shoe members disposed to be positioned between a pair of spaced apart conductors, means biasing the shoes apart, a support positioned intermediate the shoes and extending longitudinally thereof, an elongated drag plate secured to each shoe and projecting beyond the ends thereof, and means operatively connecting the drag plates at points beyond the ends of the shoes for movement toward or away from each other, said means operatively connecting the drag plates to the support so as to provide for dragging the shoes in response to movement of the support in either direction.

4. A current collector comprising, an elongated support member having spaced apart dependent legs with openings therein, a pair of collector shoes positioned intermediate the legs on the opposite sides of the support member, an elongated drag plate secured to each collector shoe and ex-

tending alongside the support member, and means operatively connecting the drag plates adjacent the ends comprising telescopic rivets passing through the openings in the dependent legs of the support member.

5. A current collector comprising, an elongated support plate having dependent legs positioned adjacent the ends with openings therein, an elongated resilient drag plate positioned on each side of the support plate having a collector shoe mounted on the outer side intermediate the ends, means positioned intermediate the collector shoes to bias them away from each other, and telescopic rivet means operatively connecting the drag plates adjacent the ends and permitting relative movement of the plates toward or away from each other, said rivet means being loosely positioned in the openings of the dependent legs of the support plate and so spaced that the distance between the centers thereof is greater than the distance between the centers of the openings.

6. In a current collector, in combination, a support plate having dependent spaced apart legs with openings therein, an elongated drag plate positioned on each side of the support plate in spaced relation with the plate, a current collector shoe mounted on each drag plate intermediate the ends thereof, telescopic means operatively connecting the drag plates adjacent the ends to provide for movement thereof relative to each other, said means passing loosely through the openings in the dependent legs of the support plate so as to provide for dragging the shoe in response to movement in either direction of the support plate, flexible shunt means connected between the dependent legs and to the shoes, and springs positioned between the collector shoes for biasing them apart.

7. In a current collector for engaging a pair of spaced apart conductors, a support having dependent spaced arms with openings adjacent the

ends, a pair of flexible conductors extending between said ends, a pair of elongated relatively flat drag plates positioned on opposite sides of the support having collector shoes secured thereto intermediate the ends on the outer sides, means connecting the ends of the drag plates to each other and to the ends of the support in movable relation, means connecting the conductors to the drag plates intermediate the ends, and resilient means biasing the drag plates apart.

8. A current collector comprising, a pair of spaced apart shoes for engaging spaced apart conductors, a drag plate secured to the adjacent side of each shoe and extending beyond the shoe, 15 a support having pairs of spaced apart dependent arms adjacent the ends of the drag plates, flexible shunt members secured between the spaced apart arms and to each shoe, spring means positioned between the drag plates to bias the shoes apart, 20 and means operatively connecting the adjacent ends of the drag plates to each other and to the dependent arms of the support.
